UNITED STATES PATENT OFFICE.

JAMES M. HAAS, OF WABASH, INDIANA.

TONGUE-SUPPORT.

SPECIFICATION forming part of Letters Patent No. 278,938, dated June 5, 1883.

Application filed May 12, 1883. (No model.)

To all whom it may concern:

Be it known that I, JAMES M. HAAS, a citizen of the United States, residing at Wabash, in the county of Wabash and State of Indiana, 5 have invented certain new and useful Improvements in Tongue and Thill Supports, of which the following is a specification, reference being had therein to the accompanying drawings.

10 My invention relates to certain new and useful improvements in tongue and thill supports.

The object of my invention is to provide a safe and durable support for shafts or thills 15 and tongues of vehicles, that said shafts and thills may be turned up to a vertical position when not in use; and, further, another object is to prevent either end of the shafts or thills from falling to the ground or against 20 the animal's heels should either end of said shafts or thills become detached from the vehicle. I accomplish these objects by means of the peculiar construction and arrangement 25 of the different parts of my device, which will be more fully pointed out and described in the specification and claims, in which—

Figure 1 is a perspective view of my device, showing the axle, bracket, end of shaft, and curved spring. Fig. 2 is a plan view of 30 the bracket, and Fig. 3 a vertical sectional view of all the parts.

Similar letters refer to similar parts throughout the drawings.

Reference being had to drawings, A represents one end of a pair of shafts or thills attached to a metal end piece, D, having its outer end enlarged and perforated in the usual form to receive a bolt, c. Axle B, of any desired form or size, is clasped by a shaft-coupling clip, C, 35 having projecting ears, perforated to receive bolt c, between which, in the usual form, the end piece, D, is held. A curved metal spring-piece, E, is secured at its outer end to the under side of end piece, D, by a clip-bolt, d, 40 said bolt being screw-threaded and provided with a nut adapted to turn up against the outer face of said spring E. The inner end of spring E is curved in S shape and the outer end adapted to fit on the under surface of end 45 piece, D, and by being held securely with bolt d the free end is permitted to spring and conform to the purpose designed. A rectangular 50 piece, F, having a cross-bar, e, at its outer end, and perforations e', adapted to register 55 with the perforations in the projecting ears of

clip C, said bracket being formed with right-angular vertical shoulders a, adapted to fit against the front face of axle B, said shoulders terminating in right-angular horizontal projections b, adapted to fit against the under face 60 of axle B, as shown in Fig. 1, the purpose of which is to prevent the end of the shaft or thill from falling or becoming entirely disconnected from axle B, and to hold the shafts in a vertical position when not in use. 65

The operation of the device is as follows: When driving or using the vehicle with an animal attached, the metal end piece, D, is frequently broken at a point between the end of the overlying wood and the enlarged perforated end, through which passes the clip-bolt c. In case of such breakage the inner curve of spring E rests by its shoulder against the inner face of cross-bar e, where, by its peculiar formation, it rests secure and prevents the end 70 of the shaft from dropping to the ground or against the animal's heels, thus preventing accidents or injury to the occupants of the vehicle; and, furthermore, when desired to place the shafts in a vertical position, the operator 75 raises the shafts until the outer curved free end of spring E fits against the cross-bar e, when the shafts are securely held in a vertical position. When desired for use, a reverse movement only is required to place the shafts 80 in position for the animal and leave the free end of spring E within the bracket F. 85

Having thus described my invention, what I claim, and desire to secure by Letters Patent, is— 90

1. A shaft-supporting device consisting of an angular bracket adapted to be bolted to a shaft-coupling and abut against the front and under face of an axle, and a curved spring secured to the shaft near its inner end, said 95 spring adapted to rest against the inner face of the cross-bar formed in said bracket, substantially as shown and specified.

2. In a shaft-supporter, the combination of the axle B, clip C, bolt c, and the angular 100 bracket F with the shaft A, the end D, clip-bolt d, and the curved spring E, all arranged and operated substantially as shown and described.

In testimony whereof I affix my signature in 105 presence of two witnesses.

JAMES M. HAAS.
